KURT WANDEL, OF NEW YORK, N. Y., ASSIGNOR, BY MIESNE ASSIGNMENTS, TO
ARKELL SAFETY BAG COMPANY, OF NEW YORK, N. Y., A CORPORATION OF
NEW YORK.

PAPER-CRINKLING MECHANISM.

Application filed May 4, 1920. Serial No. 378,745.

To all whom it may concern:

Be it known that I, KURT WANDEL, a citizen of Wurttemberg, who have declared my intention of becoming a citizen of the 5 United States, and resident of New York city, county of New York, State of New York, have invented an Improvement in Paper-Crinkling Mechanism, of which the following description, in connection with 10 the accompanying drawings, is a specification, like characters on the drawings representing like parts in each of the several views.

This invention relates to the crinkling of 15 paper to render the same stretchable and more particularly to paper crinkling mechanism employing air pressure to cause the paper to adhere to the crinkling drum for engagement and clearance therefrom by a 20 doctor or abutment which causes the crinkling in the paper. In accordance with a practice recently developed by me, this air pressure is atmospheric pressure which is made available by the use of a suction 25 device associated with the crinkling drum. In a preferred form of apparatus of this kind the crinkling drum is grooved circumferentially at intervals throughout its operative length providing a series of continuous 30 paper supporting areas which alternate with such grooves and with such grooves constituting suction areas to hold the paper continuously adherent to the drum. I have found that in the use of 35 air suction means to cause adherence of the paper to the crinkling drum, most satisfactory and effective results are obtained by having the suction effect gradually increase from a minimum where the paper 40 first engages the drum, to a maximum adjacent the crinkling point. This gradual increase of suction effect is preferably distributed over a substantial angular extent of the drum and to permit this the paper 45 web is caused to engage the drum at a substantial angular distance in advance of the doctor. A gradually increasing suction effect of this character may be provided by a suction device in the form of a suction 50 box interior of the drum, or it may be provided by suction connections located entirely exterior of the drum and I show herein forms of the invention employing both of these constructions. The forego-

ing and other objects and advantages of the 55 invention will more fully appear from the following detailed description, and the distinctive features of novelty will be thereafter pointed out in the appended claims.

Referring to the drawings:

Fig. 1 is a plan view showing a crinkling drum with a doctor associated therewith and embodying one form of the invention;

Fig. 2 is a diagrammatic vertical section 65 longitudinal of the direction of the paper movement illustrating the form of the invention of Fig. 1;

Fig. 3 is a plan view showing a crinkling drum and doctor with the invention embodied in another form; and

Fig. 4 is a vertical section showing the form of the invention of Fig. 3.

Referring first to Figs. 1 and 2, 10 indicates a crinkling drum which may be 75 equipped with smooth journal portions 10^a at its ends, this drum being mounted and driven in any suitable manner (not shown). The peripheral surface of this drum is formed with a series of circumferential 80 grooves 11 which alternate with continuous paper supporting areas 12. A doctor or clearer abutment 13 is stationarily mounted for cooperation with this drum and is equipped with a series of teeth or projections 14 which fit into the grooves 11, i. e. the operative edge of the doctor is made to fit closely and continuously the grooved periphery of the drum along the line of operative engagement. In this form of the invention the drum is formed as a hollow shell 90 and has mounted therewithin a suction box 15 having its forward edge in proximity to the doctor. The drum is formed with multiple perforations therethrough establishing communication from the grooves 11 to the suction box in the portions of such grooves that are over the suction box. The suction box 15 is connected through piping 17 with a suitable source of air suction 100 which may be an ordinary suction pump or blower. In accordance with my invention a suitable packing member 18, which may be a block of wood, extends from the back of the suction box rearwardly a substantial 105 angular distance in the direction from which the paper is being drawn, this packing block closing the holes 16 of the drum in the

proximity of the suction box. The paper web W is shown as drawn from a roll R, the direction in which the web is guided being such that the web engages the crinkling drum a substantial distance back of the doctor, i. e. approximately the same distance back as the angular extent of the packing block 18. With this arrangement a maximum of suction will be exerted upon

10 the paper in the immediate proximity of the doctor, it being noted that the suction box 15 itself is of relatively small angular extent, and that the close fitting of the doctor with the drum prevents any material

15 loss of the suction effect on the forward side of the suction box. Since the grooves 11 however are opened rearwardly, air is permitted to enter these grooves back of the point where the paper engages the drum

20 but not before by reason of the cooperation of the packing block 18 and the paper web applied to the drum periphery. By reason of this relieving of the suction back of the point where the web engages the drum, there

25 will be a gradually decreasing suction effect from a maximum at the area over the suction box to a minimum where the paper first engages the drum, and I have found this to be important and essential for the

30 proper application and effective adherence of the paper to the drum so as to present it to the doctor for the requisite and most effective crinkling effect. The provision of such a suction box with adequate packing,

35 and the perforated drum, present certain structural difficulties that add to the expense of making the same in a satisfactory manner and I have therefore devised means whereby a like suction effect progressively

40 increasing to the crinkling point may be obtained by a suction device wholly external of the drum. Such a construction is shown in Figs. 3 and 4 wherein a crinkling drum 100 similar to that already described and

45 similarly grooved is provided except however that this drum is not perforated, and need not necessarily even be hollow. The doctor 130 associated with this drum is formed with teeth or projections 140 enter-

50 ing the grooves 110 of the drum which alternate with the paper supporting areas 120. In this case however the projections 140 do not closely fit said grooves, i. e. they do not extend entirely to the bottoms of the

55 grooves. In advance of this doctor I mount a suction box 131 the forward edge of which is formed to fit the drum periphery as indicated at 132 and preferably with suitable packing to prevent the escape of the suction.

60 This suction box has piping 133 connected therewith leading to a suitable source of air suction. The paper web W in this case is led to the crinkling drum so that it engages the same at a substantial angular distance

65 back of the crinkling point in like manner

as already described. With this construction the suction effect of the suction box will be transmitted past the doctor by reason of the clearance between the projections of the doctor and the grooves of the drum 70 and this suction effect will be at its maximum directly in proximity to the doctor and gradually decreasing backwardly on the drum owing to the loss of suction as air is drawn into the grooves back of the point 75 where the paper engages the drum. In both of the described forms the paper web is first drawn easily and gently into adherence with the drum by a relatively light suction and is caused to adhere more strongly and 80 securely to the drum as it moves forward to the crinkling point and so that as it reaches the doctor it is strongly and uniformly adherent to the drum to the extent required for best crinkling effects and which may be 85 predetermined and varied by the degree of suction utilized. I am aware that the invention may be embodied in other specific forms without departing from the spirit or essential attributes thereof, and I therefore 90 desire the present embodiment to be considered in all respects as illustrative and not restrictive, reference being had to the appended claims rather than to the foregoing description to indicate the scope of the in- 95 vention.

Having described my invention, what I desire to claim as new and desire to secure by Letters Patent is:

1. Paper crinkling mechanism comprising 100 a crinkling drum and doctor cooperative therewith, and means for causing adherence of the paper to the drum by air pressure, said means constructed and arranged to cause a maximum air pressure effect in 105 proximity to the crinkling point, and gradually decreasing backward therefrom.

2. Paper crinkling mechanism comprising a crinkling drum and doctor cooperative therewith, and means for causing a progressively increasing air suction effect upon the paper as it approaches the drum to cause adherence of the paper to the drum for crinkling. 110

3. Paper crinkling mechanism comprising 115 a crinkling drum and doctor cooperative therewith, and means for causing adherence of the paper to the drum by suction with a maximum suction effect in proximity to the doctor and gradually decreasing backwardly therefrom in the direction from which the paper is drawn.

4. Paper crinkling apparatus comprising 125 a crinkling drum and doctor cooperative therewith, and means for causing adherence of the paper to the drum by suction as it is presented to the doctor, said means constructed and arranged to provide a maximum of suction effect in proximity to the doctor and with provision for relieving the 130

suction at a point relatively remote angularly therefrom in the direction from which the paper is drawn for the purpose stated.

5. Paper crinkling apparatus comprising a crinkling drum and doctor cooperative therewith, and a suction box mounted interior of the drum in proximity to said doctor, said drum having perforations therethrough to connect with said suction 10 box and a packing extending angularly interior of the drum backward from said suction box to close certain of such perforations.

6. Paper crinkling apparatus comprising a crinkling drum having its operative surface formed with a series of circumferential grooves alternating with continuous paper supporting areas, a doctor mounted to cooperate with said drum, and means for producing a suction effect in said grooves of a maximum degree in proximity to the crinkling point and gradually decreasing backward therefrom.

In testimony whereof, I have signed my name to this specification.

KURT WANDEL.
